US00D695952S

(12) **United States Design Patent**
Gordin et al.

(10) **Patent No.:** **US D695,952 S**
(45) **Date of Patent:** **** Dec. 17, 2013**

(54) **PIVOTABLE LIGHTING FIXTURE VISOR**

(71) Applicant: **Musco Corporation**, Oskaloosa, IA (US)

(72) Inventors: **Myron Gordin**, Oskaloosa, IA (US); **Timothy J. Boyle**, Oskaloosa, IA (US); **Steven T. Heaton**, Oskaloosa, IA (US)

(73) Assignee: **Musco Corporation**, Oskaloosa, IA (US)

(**) Term: **14 Years**

(21) Appl. No.: **29/455,370**

(22) Filed: **May 20, 2013**

(51) **LOC (9) Cl.** **26-99**

(52) **U.S. Cl.**

USPC **D26/120**

(57) **CLAIM**

The ornamental design for a pivotable lighting fixture visor, as shown and described.

DESCRIPTION

FIG. 1 is a perspective view of the claimed design; FIG. 2 is a top plan view of FIG. 1; FIG. 3 is a bottom plan view of FIG. 1; FIG. 4 is a front elevation of FIG. 1; FIG. 5 is a back elevation of FIG. 1; FIG. 6 is a left side elevation of FIG. 1; FIG. 7 is a right side elevation of FIG. 1; and, FIG. 8 is a view taken along section line 8-8 of FIG. 2. The broken lines shown in the drawings illustrating portions of the pivotable lighting fixture visor form no part of the claimed design.
